UNITED STATES PATENT OFFICE.

FRED LYON, OF ITHACA, NEW YORK.

WEB SHIFTER AND REGULATOR.

SPECIFICATION forming part of Letters Patent No. 642,141, dated January 30, 1900.

Application filed April 5, 1899. Serial No. 711,774. (No model.)

To all whom it may concern:

Be it known that I, FRED LYON, a citizen of the United States, residing at Ithaca, in the county of Tompkins and State of New York, have invented a new and useful Shifter and Regulator of Paper or other Flat Material in Machines, of which the following is a specification.

The chief, essential, and distinctive feature 10 of my invention consists in the use of a wheel or wheels arranged for contact with and pressure against the surface of moving paper or other material, as required, the tangent line of contact of the wheel being oblique to the 15 normal line of travel of the paper, thus producing by the friction of the periphery of the wheel a shifting or change of position of the paper or other material laterally away from said tangent line, much as the water in a running stream is deflected by an obstruction oblique to the line of the current.

In this specification and the drawings herein referred to my invention is especially described and illustrated in its application and 25 relation to "web-printing presses," so called, and other machines in which the paper or other flat material is fed to or through the press or machine in the form of a web; and the object of my invention when applied to 30 such a machine is to provide means of correcting and preventing the side motion or displacement of the web in its travel to and through the machine. For convenience in this specification I shall uniformly use the 35 word "web;" but it is here expressly stated that I do not mean to be limited to that form of material, but include any moving flat shapes of paper or other material whether propelled by tapes, rollers, or otherwise.

40 Heretofore in the class of machines mentioned, and especially in web-printing presses arranged to print directly from flat forms, type, or stereotype or otherwise, trouble has been experienced in the tendency of the web 45 to work to one side or the other on its bed coaxing or guide rolls, with the result of breaking the web, printing or folding out of place, or some or all of those results. It has thus been necessary for an attendant to give 50 more or less constant attention to keeping the web in proper place at one or more points in its course, so as to secure accurate and uni-

form register of the printing or folding, or both. The same trouble, differing in degree, is experienced with "perfecting" and "cylindrical" presses, so called, and other machines. I obviate these difficulties and attain the objects hereinabove mentioned with the device and mechanism illustrated in the accompanying drawings, in which—

55 Figure 1 is a perspective view of my invention applied at a coaxing or guide roll of a machine with mechanism for operation automatically. Fig. 2 is a top view of the principal part of my device. Fig. 3 is a vertical section of the same on the line 1-2 in Fig. 2. Fig. 4 is a vertical section of a circuit-maker and means of application and adjustment. Fig. 5 is a top view similar to Fig. 2, but with electromagnet and armature support relatively transposed. Fig. 6 is a vertical section 60 of a circuit-breaker for use with the changed construction shown in Fig. 5. Fig. 7 is a top view showing modification for using plurality of wheels. Fig. 8 is a top view showing my 65 device duplicated for collecting lateral displacement in both directions. Fig. 9 is a top view showing application of several of my devices at different parts of the same machine.

70 Similar letters refer to similar parts throughout the several views.

A is a coaxing or guide roll of a printing-press or other machine.

B is a moving web of paper, cloth, or any other material.

80 C is a support for my device, with details of attaching and adjusting in proximity omitted; but ordinary means of adjustably and rigidly attaching the support C to the machine and my invention to the support are 85 used and necessary.

D is an electromagnet.

E is a lever or armature arranged to operate in connection with the electromagnet.

F is an adjustable fulcrum-support and 90 pivot for E, situated intermediate its ends.

G is an arm or extension of E, adjustably attached at H, and I is a wheel journaled to the free end of G and free to revolve.

J is a band or tire of rubber or elastic or inflated material cemented or otherwise firmly attached to the periphery of the wheel I.

The arm G is jointed to the lever E by means of a bolt K and set-nut L or other suitable

device by which the arm may be adjusted and firmly held in relation to the web B and the lever E.

The support F is provided with set-nuts M, by means of which the height of the fulcrum-point or pivot of the lever E is variable with reference to the other parts and the proximity of the wheel I to the web is adjustable.

The mechanism and means of support of the lever E at its fulcrum-point may be any of those now in use to insure minimum friction and least lost motion. Set-screws N or other suitable means are also provided in connection with the support F to limit and adjust the lever action of E. A contact-plate or armature O is provided, either integral with the lever E or adjustable thereto.

P is a spiral spring or equivalent counter-weight adjustable in the plane of motion of the lever E. An electric circuit through the electromagnet D is provided by a battery Q located at any convenient place and wires connected in the usual manner. A circuit-maker, Fig. 4, is arranged in the circuit and attached to the press or other machine at some point in proximity to the edge of the web B.

In Fig. 4, R is a suitable support with adjustable means of attaching thereto the arm S, by which means the circuit-maker may be set in greater or less proximity to the edge of the web, as may be desired. In the construction shown a lever T is attached to the end of the arm S, with its fulcrum-point intermediate its ends. This lever is provided at U with a shoe of wood or other suitable non-conducting material, against which the web will press at times. At or near the other end of the lever a rigidly-attached arm V, at right angles therewith, and a coiled spring W are provided, the latter being adjustable in tension by means of the arm X and set-screw Y, and adjusted to normally keep the spring-plate Z, by means of the arm V, out of contact with the spring-plate z. One end of the plate Z is attached to the binding-post a, and one end of the plate z is attached to the binding-post b. The wires are attached to these posts by set-nuts c c, and thus the circuit made continuous whenever the edge of the web presses against the lever U sufficiently to allow contact of Z with z. The adjustment may be as delicate as desired, so that the least pressure of the edge of the web at U will make the contact. The wires may be extended to and connect the battery and magnet in circuit in the usual manner, and insulation may be provided in all parts necessary. Any commercial electric current may be used instead of a battery and any form of electromagnet which depends upon an electric current. For convenience I illustrate the simplest form.

The lever E in actual construction and application of my device may be in any form or shape and the electromagnet in any position relatively thereto, and the wheel I may be journaled directly to the lever E without the arm G. Said wheel may also be attached di-

rectly or by arm G at any point along the lever E or relatively to magnet, fulcrum-point, spring, or counterweight; but in any construction and application of my device it is necessary that by means of the fulcrum-support or otherwise the lever E and the wheel I shall be prevented from being deflected from their respective planes of motion. 75

I now proceed to describe the actual operation of my invention when automatically arranged, as hereinabove described, with this reminder, that its automatic action depends on a normally open circuit, the electromagnet D being in consequence normally inactive. 80

The lever E and contact-plate O are so adjusted by the means described that they are normally held away from the electromagnet 85 D when the circuit is open and the wheel I raised from contact with the web B.

The wheel I is so adjusted by the arm G; as shown in Figs. 2 and 3, or by the position of the lever E that when the periphery of the wheel is brought in contact with the web and pressed upon it the tangent line of contact is more or less oblique to the sides or line of travel of the web and angled away from the direction in which it is intended to have the wheel operative to slide or shift the paper. When the web becomes out of place, so that its edge crowds against the shoe U, contact of the plate Z with the plate z is made, the electromagnet is energized, and the lever E and the armature O are 90 attracted or pulled toward the electromagnet, and the wheel I accordingly is brought in contact with the web and presses against it and the roll and by its pressure and friction is instantly operative to push and move the web 100 laterally and continues so to do until the pressure of the edge of the web against the lever T of the circuit-maker ceases, when the circuit opens, the electromagnet loses its attracting energy, the lever and armature recede from 105 the magnet, and the wheel I is removed from contact and pressure upon the web and held in that position until the web becomes again out of place.

A very slight obliquity of the tangent line 115 of contact with the line of travel of the material is sufficient to produce the shifting laterally, and this angle is adjustable by the means hereinabove described.

It will readily be seen that to automatically 120 correct the side motion of the web in both directions an entire duplication of the mechanism is necessary, the only difference being that the tangent lines of contact of the two wheels must be oblique to the line of travel 125 of the web in opposite directions to each other. This is shown by the dotted wheel and arm in Fig. 2. The circuit-maker for each would of course be attached on the side opposite to that toward which the respective mechanism 130 is to operate to shift the web. The two shifters may be set close together in the same support or they may be set one near each edge of the web or one or both at any point intermediate.

Fig. 8 shows the arrangement of two shifters for this purpose on the same machine. It may also be found useful to apply my shifters either singly or in pairs at several different places in the same machine, depending on its construction, use, and the kind and quality of the web. This is shown in Fig. 9 of the drawings.

The wheel I does not seem to be as effective 10 in its operation without the rubber or elastic band or tire which is used to increase the friction or grip on the web. By the adjustment of the lever E the pressure of the wheel and proportionally its friction on the web 15 may be regulated within certain limits. The strength or energy of the electromagnet is also usable as a factor for this purpose. It is also hereby understood that the width of tire or tread of the wheel may be varied to 20 accomplish the objects sought.

In Fig. 7 is illustrated another means of increasing the effectiveness and usefulness as well as shifting power of my invention by mounting two or more wheels I by means of 25 their arms G to a cross-arm g, the latter being adjustably attached to the lever E, it being necessary, of course, that the tangent lines of contact with the surface of the web of the wheels so mounted shall be parallel. A plurality of wheels may also be journaled directly or by means of arms along the lever E for use for shifting purposes in some forms 30 of machines.

The point of application of my device to 35 any machine for the purpose specified will be at any part where necessary for efficiency and convenience at which the intervening paper or other flat material may be pressed by the wheel against an adjacent unyielding smooth 40 surface already existing or which may be applied. This surface may be either flat or curved, stationary or in motion. I therefore do not mean to limit the application of my invention to a coaxing or guide roll as shown 45 in the drawings.

Fig. 5 shows relatively to the wheels the portions of the electromagnet and armature support or fulcrum-point transposed and a weight P used as an equivalent of the spiral 50 spring. Fig. 6 is a circuit-breaker for use with the changed positions shown in Fig. 5. It will be seen that in these constructions a closed circuit will be the normal condition and the pressure of the edge of the web against 55 the end or shoe U of the lever T in Fig. 6 serves to break the electric circuit by allowing the spring-plates Z and z to separate, which normally are held in contact by the spring W, the arm X, and set-screws Y. 60 This adjustment is accomplished by changing the position of the arm V so as to press against z instead of Z, as in the circuit-maker, Fig. 4, hereinabove described.

Upon comparison of the two constructions, 65 Figs. 2 and 5, it will be seen that in Fig. 5 the pressure of the wheel I on the web and roll

will depend on the weight of the wheel and the spring or balance adjustment of the lever E whenever the circuit is broken and the electromagnet releases the lever E, which is normally attracted. In Figs. 2 and 3, on the other hand, the pressure of the wheel will depend on the strength and pull of the electromagnet, which quality will depend on its construction or the strength of the electric current, or both. 70 75

The construction shown in Figs. 2 and 3 will be more positive and delicate in operation and will admit of a wider range of efficiency and application, and both constructions relate to the automatic operation of my invention. 80

I make no separate claim of novelty for the use and adaptation of an electric circuit, electromagnet, circuit makers and breakers, &c., 85 except in combination with my device of a shifter wheel or wheels operated as hereinabove described.

Other means of automatic operation doubtless will be thought of; but it is believed the 90 employment of an electromagnet and an electric current will be found most efficient and economical.

In the mechanisms hereinabove shown and described the shifter-wheel I is mounted to 95 press against the material whenever required. I do not limit myself to that manner of operation, but include any means by which the material and wheel are brought in contact and pressure against each other. For example, 100 the wheel I could be fixedly mounted at the requisite angle in proximity to the surface of the material and a roller operated automatically or otherwise to press upon the opposite surface of the material and put the latter in 105 contact and pressure upon the wheel, and thereby make operative the shifting action of the latter. This roller may be similar to or a duplicate of said wheel and arranged to come in contact with and press said material 110 against said wheel directly opposite, and in the same or a parallel line of contact, thus making both wheel and rollers simultaneously operative to shift the material laterally. 115

I am aware that guide-rolls of paper-machines have been mounted on a middle pivoted frame and that in connection therewith adjustable friction-rolls have been used adapted to grip the edge of the web when laterally displaced. I do not claim any such construction. In my invention the wheel is rigidly journaled in proximity to the paper or material, with its plane of revolution intersecting the surface of said material always obliquely to the line of travel of said material 125 and is not normally in contact with the material. The wheel is brought in contact with and presses upon the surface of the web or other material only when and as desired to correct lateral displacement, and is removed 130 from contact and pressure as soon as the correction is made. 135

What I claim as my invention, and desire to secure by Letters Patent of the United States, is—

1. A shifter and regulator of moving paper or other flat material in a machine, and consisting of a lever and a wheel journaled thereon, the lever being mounted in proximity to said material and in such relation thereto that the lever may be actuated at will to bring the periphery of the wheel in contact with the surface of said material in a tangent line of contact oblique to the line of travel of said material, and thereby press against the latter, with means to prevent deflection of the lever and the wheel from their respective planes of motion, substantially as described.
2. A shifter and regulator of moving paper or other flat material in a machine, and consisting of a lever and a wheel journaled thereon, a band or tire of rubber or elastic or inflated material rigidly affixed to the periphery of the wheel, the lever being mounted in proximity to said material and in such relation thereto that the lever is actuated at will to bring the periphery of the wheel in contact with the surface of said material in a tangent line of contact oblique to the line of travel of said material, and thereby press against the latter, with means to prevent deflection of the lever and the wheel from their respective planes of motion, substantially as described.
3. A shifter and regulator of moving paper or other flat material in a machine, and consisting of a lever and a wheel journaled thereon, the lever rigidly and adjustably mounted in proximity to said material and in such relation thereto that the lever is actuated at will to bring the periphery of the wheel in contact with the surface of said material in a tangent line of contact oblique to the line of travel of said material, and thereby press against the latter, with means to prevent deflection of the lever and the wheel from their respective planes of motion, substantially as described.
4. A shifter and regulator of moving paper or other flat material in a machine, and consisting of a lever, an arm attached thereto, a wheel journaled to said arm, the lever mounted in proximity to said material and in such relation thereto that the lever is actuated at will to bring the periphery of the wheel in contact with the surface of said material in a tangent line of contact oblique to the line of travel of said material, and thereby press against the latter, with means to prevent deflection of the lever and the wheel from their respective planes of motion, substantially as described.
5. A shifter and regulator of moving paper or other flat material in a machine, and consisting of a lever, an arm attached thereto, a wheel journaled to said arm, the lever rigidly and adjustably mounted in proximity to said material and in such relation thereto that the lever is actuated at will to bring the

periphery of the wheel in contact with the surface of said material in a tangent line of contact oblique to the line of travel of said material, and thereby press against the latter, with means to prevent deflection of the lever and the wheel from their respective planes of motion, substantially as described.

6. A shifter and regulator of moving paper or other flat material in a machine, and consisting of a lever, an arm adjustably attached thereto, a wheel journaled to said arm, the lever mounted in proximity to said material and in such relation thereto that the lever is actuated at will to bring the periphery of the wheel in contact with the surface of said material in a tangent line of contact oblique to the line of travel of said material, and thereby press against the latter, with means to prevent deflection of the lever and the wheel from their respective planes of motion, substantially as described.

7. A shifter and regulator of moving paper or other flat material in a machine, and consisting of a lever, an arm adjustably attached thereto, a wheel journaled to said arm, the lever rigidly and adjustably mounted in proximity to said material and in such relation thereto that the lever is actuated at will to bring the periphery of the wheel in contact with the surface of said material in a tangent line of contact oblique to the line of travel of said material, and thereby press against the latter, with means to prevent deflection of the lever and the wheel from their respective planes of motion, substantially as described.

8. A shifter and regulator of moving paper or other flat material in a machine, and consisting of a lever and a wheel journaled thereon, the lever being mounted in proximity to said material and in such relation thereto that the lever is actuated at will to bring the periphery of the wheel in contact with the surface of said material in a tangent line of contact oblique to the line of travel of said material, and thereby press the latter against an adjacent, unyielding smooth surface, with means to prevent deflection of the lever and the wheel from their respective planes of motion, substantially as described.

9. A shifter and regulator of moving paper or other flat material in a machine, and consisting of a lever and a wheel journaled thereon, the lever rigidly and adjustably mounted in proximity to said material and in such relation thereto that the lever is actuated at will to bring the periphery of the wheel in contact with the surface of said material in a tangent line of contact oblique to the line of travel of said material, and thereby press the latter against an adjacent, unyielding smooth surface, with means to prevent deflection of the lever and the wheel from their respective planes of motion, substantially as described.

10. A shifter and regulator of moving paper or other flat material in a machine, and consisting of a lever, an arm attached thereto, a wheel journaled to said arm, the lever mount-

ed in proximity to said material and in such relation thereto that the lever is actuated at will to bring the periphery of the wheel in contact with the surface of said material in a tangent line of contact oblique to the line of travel of said material, and thereby press the latter against an adjacent, unyielding smooth surface, with means to prevent deflection of the lever and the wheel from their respective planes of motion, substantially as described.

11. A shifter and regulator of moving paper or other flat material in a machine, and consisting of a lever, an arm attached thereto, a wheel journaled to said arm, the lever rigidly and adjustably mounted in proximity to said material, and in such relation thereto that the lever is actuated at will to bring the periphery of the wheel in contact with the surface of said material in a tangent line of contact oblique to the line of travel of said material, and thereby press the latter against an adjacent, unyielding, smooth surface, with means to prevent deflection of the lever and the wheel from their respective planes of motion, substantially as described.

12. A shifter and regulator of moving paper or other flat material in a machine, and consisting of a lever, an arm adjustably attached thereto, a wheel journaled to said arm, the lever mounted in proximity to said material and in such relation thereto that the lever is actuated at will to bring the periphery of the wheel in contact with the surface of said material in a tangent line of contact oblique to the line of travel of said material, and thereby press the latter against an adjacent, unyielding, smooth surface, with means to prevent deflection of the lever and the wheel from their respective planes of motion, substantially as described.

13. A shifter and regulator of moving paper or other flat material in a machine, and consisting of a lever, an arm adjustably attached thereto, a wheel journaled to said arm, the lever rigidly and adjustably mounted in proximity to said material, and in such relation thereto that the lever is actuated at will to bring the periphery of the wheel in contact with the surface of said material in a tangent line of contact oblique to the line of travel of said material, and thereby press the latter against an adjacent, unyielding, smooth surface, with means to prevent deflection of the lever and the wheel from their respective planes of motion, substantially as described.

14. A shifter and regulator of moving paper or other flat material in a machine, and consisting of a lever, a plurality of wheels journaled thereto, with their planes of revolution parallel to each other, the lever being mounted in proximity to said material and in such relation thereto that the lever is actuated at will to bring the periphery of all the wheels simultaneously in contact with the surface of said material in tangent lines of contact oblique to the line of travel of said material,

and thereby press against the latter, with means to prevent deflection of the lever and the wheels from their respective planes of motion, substantially as described.

15. A shifter and regulator of moving paper or other flat material in a machine, and consisting of a lever, a plurality of wheels journaled thereto with their planes of revolution parallel to each other, the lever being mounted in proximity to said material and in such relation thereto that the lever is actuated at will to bring the peripheries of all the wheels simultaneously in contact with the surface of said material in tangent lines of contact oblique to the line of travel of said material, and thereby press the latter against an adjacent, unyielding, smooth surface, with means to prevent deflection of the lever and the wheels from their respective planes of motion, substantially as set forth.

16. A shifter and regulator of moving paper or other flat material in a machine, and consisting of a lever, a plurality of arms thereto attached, one or more wheels journaled to each arm, with the planes of revolution of all of the wheels parallel to each other, the lever being mounted in proximity to said material and in such relation thereto that the lever is actuated at will to bring the peripheries of all the wheels simultaneously in contact with the surface of said material in tangent lines of contact oblique to the line of travel of said material, and thereby press against the latter, with means to prevent deflection of the lever and the wheels from their respective planes of motion, substantially as set forth.

17. A shifter and regulator of moving paper or other flat material in a machine, and consisting of a lever, a plurality of arms thereto attached, one or more wheels journaled to each arm, with the planes of revolution of all of the wheels parallel to each other, the lever being mounted in proximity to said material and in such relation thereto that the lever is actuated at will to bring the peripheries of all the wheels simultaneously in contact with the surface of said material in tangent lines of contact oblique to the line of travel of said material, and thereby press the latter against an adjacent, unyielding, smooth surface, with means to prevent deflection of the lever and the wheels from their respective planes of motion, substantially as set forth.

18. In a shifter and regulator of moving paper or other flat material in a machine, a wheel rigidly journaled in proximity to said material, with its plane of revolution intersecting the surface of said material always obliquely to the line of travel of said material, with means to at will press said wheel against said surface, as set forth.

19. In a shifter and regulator of moving paper or other flat material in a machine, a plurality of wheels rigidly journaled in proximity to said material, with their planes of revolution parallel and intersecting the surface of said material always obliquely to the

line of travel of said material, with means to at will press said wheels simultaneously against said surface, as set forth.

20. In a shifter and regulator of moving paper or other flat material in a machine, two wheels mounted in proximity to said material with their planes of revolution intersecting the surface of said material obliquely (by opposite angles) to the line of travel of said material, with means to at will press either of said wheels against said surface, as set forth.

21. In a shifter and regulator of moving paper or other flat material in a machine, a plurality of wheels mounted in series in proximity to said material, with the respective planes of revolution of the wheels of each series parallel and intersecting the surface of said material obliquely to the line of travel of said material, with means to at will press any series of said wheels simultaneously against said surface, substantially as described.

22. In combination with the moving paper or other flat material in a machine, a wheel rigidly journaled in proximity to said material with its plane of revolution intersecting the surface of said material always obliquely to the line of travel of said material, an unyielding, smooth surface forming part of said machine and adjacent to one of the surfaces of said material but independent of said wheel, and means to at will bring said wheel in contact with the opposite surface of said material and thereby press the latter against said smooth surface, substantially as set forth.

23. In combination with the moving paper or other flat material in a machine, a plurality of wheels rigidly journaled in proximity to said material, with their planes of revolution parallel, and intersecting the surface of said material always obliquely to the line of travel of said material, an unyielding, smooth surface forming part of said machine and adjacent to one of the surfaces of said material but independent of said wheels, and means to at will bring said wheels simultaneously in contact with the opposite surface of said material, and thereby press the latter against said smooth surface, substantially as set forth.

24. In combination with the moving paper or other flat material in a machine, a plurality of wheels mounted in proximity to said material with their respective planes of revolution intersecting the surface of said material obliquely to the line of travel of said material, an unyielding smooth surface forming part of said machine and adjacent to one of the surfaces of said material, and means to at will bring any wheel, or in series, two or more, said wheels revolving in the same or parallel planes, in contact with the opposite surface of said material, and thereby press the latter against said smooth surface, substantially as set forth.

25. In combination with a shifter and regulator of moving paper or other flat material in a machine, and consisting of a wheel rig-

idly journaled in proximity to the surface of said material with its plane of revolution intersecting said surface always obliquely to the line of travel of said material, an electric circuit, an electromagnet in said circuit, a circuit maker or breaker actuated by the edge of said material and an armature adapted to make said wheel operative upon the surface of said material, as set forth.

26. In combination with a shifter and regulator of moving paper or other flat material in a machine, and consisting of a wheel rigidly journaled in proximity to the surface of said material, with its plane of revolution intersecting said surface always obliquely to the line of travel of said material, a normally-open electric circuit, an electromagnet in said circuit, the armature adapted to make said shifter operative upon the surface of said material whenever and as long as the circuit is closed, and a circuit-maker actuated by the edge of said material, as set forth.

27. In combination with a shifter and regulator of moving paper or other flat material in a machine, and consisting of a wheel rigidly journaled in proximity to the surface of said material with its plane of revolution intersecting said surface always obliquely to the line of travel of said material, a normally-closed electric circuit, an electromagnet in said circuit, the armature adapted to make said shifter inoperative whenever and as long as the circuit is closed, and a circuit-breaker actuated by the edge of said material, as set forth.

28. In combination with a machine in which paper or other flat material is normally in motion, one or more wheels rigidly journaled in proximity to the surface of said material, with their respective planes of revolution intersecting the said surface always obliquely to the line of travel of said material, an unyielding smooth body in proximity to the opposite surface and opposite said wheels, but independent thereof, and means to press said wheel or wheels against said intervening material and the latter against said body, the contact and pressure of said wheel or wheels being operative to shift said material laterally as desired, substantially as described.

29. In combination with a machine in which paper or other flat material is normally in motion, wheels mounted in proximity to the surface of said material, with their respective planes of revolution intersecting the said surface obliquely to the line of travel of said material, an unyielding, smooth body in proximity to the opposite surface, and opposite said wheels, and means to press said wheels independently of each other against said intervening material, and the latter against said body, the contact and pressure of said wheels independently being operative to shift said material laterally as desired, substantially as described.

30. In combination with a machine in which paper or other flat material is normally in mo-

tion, wheels mounted in proximity to the surface of said material with their respective planes of revolution intersecting the said surface obliquely to the line of travel of said material, an unyielding, smooth body in proximity to the opposite surface, and opposite each of said wheels, and means to press said wheels independently of each other against said intervening material and the latter against said body, the contact and pressure of said wheels being independently operative to shift said material laterally as desired, substantially as described.

31. In combination with a machine in which paper or other flat material is normally in motion, a wheel mounted in proximity to the surface of said material with its plane of revolution intersecting the said surface obliquely to the line of travel of said material, an unyielding, smooth body in proximity to the opposite surface and opposite said wheel, means to automatically press said wheel against said intervening material and the latter against said body, the contact and pressure being operative to shift said material laterally as desired, and means to automatically intermit said contact and pressure, as set forth.

32. In combination with a machine in which paper or other flat material is normally in motion, wheels mounted in proximity to the surface of said material with their respective planes of revolution intersecting the said surface obliquely to the line of travel of said material, an unyielding, smooth body in proximity to the opposite surface and opposite each of said wheels, independent means to automatically press each or any of said wheels against said intervening material and the latter against said body, the contact and pressure being operative to shift said material laterally as desired, and means to automatically intermit said contact and pressure, as set forth.

33. A shifter and regulator of moving paper or other flat material in a machine, and consisting of a wheel mounted in proximity to said material with its plane of revolution intersecting the surface of said material obliquely to the line of travel of said material, a roller mounted in proximity to the other surface of said material and directly opposite said wheel, with means to at will press said roller against said intervening material and the latter against said wheel, operative to shift said material laterally, as set forth.

34. A shifter and regulator of moving paper or other flat material in a machine, and consisting of a plurality of wheels mounted in proximity to said material, with their respective planes of revolution intersecting the surface of said material obliquely to the line of travel of said material, a plurality of rollers mounted in proximity to the other surface of said material and respectively directly opposite said wheels, with means to at will press said rollers against said intervening material

and the latter against said wheels, operative to shift said material laterally, as set forth.

35. A shifter and regulator of moving paper or other flat material in a machine, and consisting of a wheel mounted in proximity to said material, with its plane of revolution intersecting the surface of said material obliquely to the line of travel of said material, a smooth body mounted in proximity to the other surface of said material and directly opposite said wheel, with means to at will press said body against said intervening material and the latter against said wheel, operative to shift said material laterally, as set forth.

36. A shifter and regulator of moving paper or other flat material in a machine, and consisting of a wheel mounted in proximity to said material, with its plane of revolution intersecting the surface of said material obliquely to the line of travel of said material, a wheel mounted in proximity to the other surface of said material and directly opposite said first-mentioned wheel, and with its plane of revolution intersecting said material coincidently with that of said first-mentioned wheel, with means to at will press said wheels against the intervening material and thereby shift the same laterally, as set forth.

37. In combination with a "web-printing press," so called, or other machine in which the paper or other flat material is fed to or through the press or machine in the form of a web, a wheel mounted in proximity to a coaxing or guide roll, with the said web intervening, the plane of revolution of said wheel intersecting the surface of said web obliquely to its line of travel, and means to at will bring said wheel in contact with said web and press the same against said roll, thereby making said wheel operative to shift said web laterally, as set forth.

38. In a "web-printing press," so called, or other machine in which the paper or other flat material is fed to or through the press or machine in the form of a web, a plurality of wheels mounted in proximity to a coaxing or guide roll, with the said web intervening, the respective planes of revolution of said wheels intersecting the surface of said web obliquely to its line of travel, with means to at will bring any of said wheels into contact with and pressure against said web, and shift the web laterally, as set forth.

39. In a "web-printing press," so called, or other machine in which the paper or other flat material is fed to or through the press or machine in the form of a web, a plurality of wheels mounted in proximity to a coaxing or guide roll, with the said web intervening, the respective planes of revolution of said wheels intersecting the surface of said web obliquely to its line of travel, with means to at will bring the wheels revolving in parallel planes into contact with and pressure against said web, and thereby shift the web laterally, as set forth.

40. In a "web-printing press," so called, or other machine in which the paper or other flat material is fed to or through the press or machine in the form of a web, the web shifting and regulating mechanism herein described consisting of one or more wheels rigidly journaled in proximity to the surface of said material, and whose respective planes of revolution intersect said surface always obliquely to the line of travel of said material automatically controlled and operative by an electric

circuit, an electromagnet in said circuit, the armature actuating the shifter wheel or wheels, and a circuit maker or breaker actuated by the edge of the web, as set forth. ¹⁵

In testimony whereof I affix my signature in presence of two witnesses.

FRED LYON.
